(57) CLAIM

The ornamental design for a flower planter, as shown and described.

DESCRIPTION

FIG. 1 is a perspective view of a flower planter showing my new design;

FIG. 2 is a front elevational view thereof;

FIG. 3 is a left side elevational view thereof, the right side elevational view being the mirror image; and,

FIG. 4 is a top plan view thereof.

The broken line showing in FIG. 4 is for illustrative purposes only and forms no part of the claimed design.
